SAMUEL N. SENNA, OF HOLYOKE, MASSACHUSETTS, ASSIGNOR TO B. F. PERKINS & SON, INC., OF HOLYOKE, MASSACHUSETTS, A CORPORATION OF MASSACHUSETTS.

LUBRICATED FAN-MOUNTING.

1,328,017.

Specification of Letters Patent. Patented Jan. 13, 1920.

Application filed March 8, 1919. Serial No. 281,485.

To all whom it may concern:

Be it known that I, SAMUEL N. SENNA, a citizen of the United States of America, residing at Holyoke, in the county of Hampden and State of Massachusetts, have invented certain new and useful Improvements in Lubricated Fan-Mountings, of which the following is a specification.

My invention relates to motor driven fans and more particularly to a lubricated fan mounting.

There has been developed an electrically driven fan, popularly known as a "man cooler." These fans are used, for example, in steel mills about the furnaces, to cool the men working about the furnace. Because of the intense heat to be counteracted, the fans must be very powerful and travel at very high speed; and yet must be portable, say, carried on pedestals. The combining of these two features, portability and great power, presents a peculiarly difficult problem. For, if portability is to be secured, the fan and its motor must be, in practical effect, a single unit with the fan carried directly upon the motor shaft; in spite of the fact that the motor-shaft bearings of the commercial electric motor are ill-fitted to withstand the powerful thrusts exerted by the fan. I have devised a fan mounting directly applicable to the usual commercial electric motor, which provides for the proper taking up of the fan's thrust loads, and for the lubricating of the bearing parts by the utilization of parts present in the usual commercial motor.

One object of my invention is to provide a fan mounting immediately applicable to commercial electric motors which mounting will properly take care of the thrust loads imposed by the fan.

Another object is to provide a proper lubricating means,—utilizing provisions upon the shaft of the usual commercial motor,—for lubricating a mounting such as that just above indicated.

To these ends, and also to improve generally upon devices of the character indicated, my invention consists in the following matters hereinafter described and claimed.

In the accompanying drawings, Figure 1 is a perspective view of a "man-cooler" fan to which my invention is applied, and Fig. 2 is a diametrical cross-sectional view of a fan mounting embodying my invention.

The hub 1 of the fan carries the usual blades 2, as by having their shanks 3 screwed into the recesses 4 and held by set screws 5. The hub is provided with the usual bore 6 to receive the shaft S of the electric motor 60 M, the bore having the usual keyway 7 extending from end to end thereof, and the set screw 8.

According to the invention, the bore 6 is considerably enlarged at its inner end to 65 present an annular recess 9, affording an annular shoulder 10, and a circular wall 11. This recess is designed to receive an annular plate-thrust ball-bearing B composed of plates 12, 12, each with a raceway 13, and 70 balls 14 traveling upon the raceways. Also, the hub is provided with a lubricant passage, or duct, 15 extending from the exterior of the hub into the bore 6 at the keyway 7 and arranged preferably obliquely to the bore. 75 An oil cup 16 is preferably provided as shown.

The structure just described is immediately applicable to the usual commercial motor. Such a motor has the shaft S with 80 a keyway 17 extending through the exposed length thereof, and also has a stationary part or abutment, as a projecting bushing 18, surrounding the inner end of the exposed portion of the shaft.

In mounting the described fan upon the shaft S, a key 19 is used of a length sufficiently short to provide that the key does not extend across or close the entrance to the duct 15 and leaves a portion of the keyway 90 17 unoccupied. The hub, with the bearing B carried therein, is slid along the shaft sufficiently to back the rear plate of the bearing against the projection 18, so that the thrust loads of the fan, which act to the left as 95 viewed in Fig. 2, and are, of course, caused by the air pressure upon the fan blades, are transmitted through the bearing and taken by the projection 18 which, for present purposes, may be considered as a part of the motor casing. Of course, the wall 10 backs against the forward plate of the bearing. Oil from the duct 15 passes into the unoccupied portions of the keyways 7 and 17 and, so, is fed to the bearing B, being retained by 105 the wall 11 and the rear plate 12.

It will be seen that I have provided a fan mounting immediately applicable to commercial motors, which mounting properly takes care of the thrust loads imposed by the 110

fan, and which includes a proper lubricating means, utilizing provisions upon the shaft of the motor.

What I claim is—

- 5 1. The combination with a motor having a shaft projecting from one end of its casing and a keyway in said projecting portion, a hub on said projecting portion and having a keyway therein; a recess provided in the hub adjacent the motor casing, a thrust bearing in said recess, and a key of less length than the keyways and engaged therein so as to leave portions thereof adjacent said bearing unoccupied, and a lubricant duct communicating from the exterior of the hub with said unoccupied portions, whereby lubricant may be fed to the bearing through said duct and keyways.
- 10 2. In a fan mounting, in combination, a motor presenting a projecting shaft and a stationary abutment adjacent the inner end of the projecting portion of said shaft, said shaft being provided with a keyway extending therealong and having a portion adjacent said inner end, a fan presenting a hub mounted upon said shaft and formed at its inner end to provide a bearing-receiving recess, said hub having a keyway therealong, a plate-thrust bearing received in said recess engaging said abutment with its rear plate and the bottom of said recess with its forward plate, a key received in, and of less
- 15 30

length than, the keyway of the shaft and located therein to leave that portion of such keyway adjacent said recess and bearing unoccupied, said hub also being provided with a lubricant duct communicating from the exterior of said hub with the said unoccupied portion, whereby lubricant may be fed to said bearing through said duct and keyways.

3. In a fan mounting, in combination, a motor presenting a projecting shaft and a stationary abutment adjacent the inner end of the projecting portion of said shaft, said shaft being provided with a keyway extending therealong and having a portion adjacent said inner end, a fan presenting a hub mounted upon said shaft and formed at its inner end to provide a bearing-receiving recess, said hub having a keyway therealong and having a portion adjacent said recess, a plate-thrust bearing received in said recess engaging said abutment with its rear plate and the bottom of said recess with its forward plate, a key received in, and of less length than, said keyways and located to leave the portions of such keyways adjacent said recess and bearing unoccupied, said hub also being provided with a lubricant duct communicating from the exterior of said hub with the said unoccupied portions, whereby lubricant may be fed to said bearing through said duct and keyways.

SAMUEL N. SENNA.
